UNITED STATES PATENT OFFICE.

GEORGE E. ROCKDASCHEL, OF SUMNER, IOWA.

HARNESS-HOOK.

1,010,958.

Specification of Letters Patent.

Patented Dec. 5, 1911.

Application filed April 8, 1911. Serial No. 619,801.

To all whom it may concern:

Be it known that I, GEORGE E. ROCKDASCHEL, a citizen of the United States, residing at Sumner, in the county of Bremer and State of Iowa, have invented certain new and useful Improvements in Harness-Hooks, of which the following is a specification, reference being had therein to the accompanying drawing.

10 This invention relates to devices for suspending harness on the wall of a barn or stable which are in the form of a hook or peg.

15 The invention has for its object to provide an improved device of this kind which is detachably held in position to support a harness and which, when released, will automatically operate to permit the harness to slide off of the support.

20 Referring to the accompanying drawings:—Figure 1 is a view in perspective of a harness supporting device constructed in accordance with this invention. Fig. 2 is an enlarged side view thereof with a portion 25 of the device in vertical section. Fig. 3 is a plan view of the device shown in Fig. 1 with the outer end of the support broken away.

This invention comprises in its general 30 features a bracket adapted to be secured to the wall of a barn or stable, a harness supporting arm hinged to said bracket, and a lever which normally holds said arm in position to support the harness, and serves to 35 automatically release the arm and permit the harness to be released therefrom.

In carrying out the invention, an arm 1 is provided of any suitable form and construction which is hinged to a bracket 2 40 adapted to be secured to the wall of a barn or stable, said bracket being of any suitable construction, and an operating arm 3 which normally engages the harness supporting arm and is adapted to release the 45 same, when the harness is to be removed. In conjunction with the harness supporting arm is a spring which serves to permit the arm when released to swing downwardly and to return it to its normal position when 50 the harness has been removed therefrom.

The arm 1, as here shown, preferably consists of two flat narrow strips of metal having the harness supporting portion composed of the two flat members 5 lying close 55 to each other and terminating in a point 6 at the outer end of the arm. The arm so

formed is slightly curved upward toward its outer end, as shown. The inner ends of the members 5 are bent outwardly to form the shoulders 7, and from said shoulders 7 the metallic strips extend rearward a short distance forming the spaced members 8.

60 The bracket 2 is preferably constructed of two short strips of angle iron 9 which are spaced apart from each other and secured to the wall 10 of a barn or stable.

65 The inner ends of the members 8 are hinged to the bracket 2 by a pivot pin 11. The arm 3 is formed with a handle portion 12 depending from the flattened portion 13 which projects up between the spaced members 8 and being somewhat reduced in thickness extends up to the laterally projecting portion 14 which projects between the angle irons 9 and is hinged thereto by the pivot 70 pin 15. The arm 1 is held normally in horizontal position as shown by means of a pin 16 mounted in the members 8 which rest in a notch 17 in the flattened portion 13 of the arm 3. The weight of the harness hung 75 upon the arm 1 holds the pin 16 in the notch 17. The coil spring 4 is connected at one end to the member 14 of the arm 3, and at its other end to a pin 18 mounted in the members 8.

80 When it is desired to remove the harness suspended from the arm 1, the arm 3 is pulled outward so as to disengage the notch 17 from the pin 16 and the weight of the harness causes the arm 1 to be pulled down 85 to an inclined position as shown in dotted lines in Fig. 2, thereby permitting the harness to slide off of the arm 1. When the arm 1 is relieved of the harness the coil 90 spring 4 which is under tension, automatically throws back the arm 1 to its normal horizontal position, the arm 3 being also swung by the spring 4 so as to cause the notch 17 to engage the pin 16.

95 It will be seen that by means of this invention a simple device is provided for supporting harness which may be easily operated to permit the harness to be readily released from its support.

100 What I claim is:—

1. In a device of the kind described, a bracket, a horizontal harness supporting arm hinged to said bracket, a depending arm detachably engaged to said harness supporting arm and supporting it in horizontal 110 position, and having a lateral projection at its upper end hinged to said bracket, and a

spring connected at one end to said horizontal arm and at its other end to the lateral projecting end of the depending arm.

- 5 2. In a device of the kind described, a bracket, a horizontal harness supporting arm hinged to said bracket, a vertical depending arm detachably engaging said harness supporting arm and supporting it in horizontal position and having a lateral 10 projection at its upper end hinged to said bracket, and a coil spring connected at one end to said horizontal arm and at its other end to the lateral projection at the top of the depending arm.
- 15 3. In a device of the kind described, a bracket consisting of a pair of short angle irons spaced apart from each other, a harness supporting arm consisting of two metallic strips extending close together at

the outer portion of the arm and having 20 rearwardly extending spaced members hinged to said bracket, a pin extending between said spaced members, a depending vertical arm extending between said spaced members and having a notch engaging said pin, and a lateral projection at its upper end hinged to said angle irons, and a coil spring connected at one end to the rear end of said harness supporting arm and at its other end to the lateral projection of the depending arm. 25 30

In testimony whereof I hereunto affix my signature in presence of two witnesses.

GEORGE E. ROCKDASCHEL.
